UNITED STATES PATENT OFFICE.

JOHN J. SCHILLINGER, OF NEW YORK, N. Y.

MANUFACTURE OF BUILDING-BLOCKS.

SPECIFICATION forming part of Letters Patent No. 252,263, dated January 10, 1882.

Application filed October 11, 1881. (No model.)

To all whom it may concern:

Be it known that I, JOHN J. SCHILLINGER, a citizen of the United States, residing at New York, in the county and State of New York, have invented new and useful Improvements in the Manufacture of Building-Blocks, of which the following is a specification.

This invention consists in a building-block two opposite faces of which are provided with 10 cavities, the cavities in each of said faces extending to within a short distance from the opposite face, while the remaining faces present solid or unbroken surfaces; also, in the process for manufacturing such building-blocks, 15 as hereinafter more fully pointed out.

This invention is illustrated in the accompanying drawings, in which Figure 1 represents a perspective view of a building-block made according to my invention. Fig. 2 is a 20 section of the same in the plane $x-x$, Fig. 1. Fig. 3 is a transverse section of the same in the plane $y-y$, Fig. 1. Fig. 4 illustrates a portion of the mechanism which I use in manufacturing my building-blocks.

25 Similar letters indicate corresponding parts.

In the example shown in the drawings the letter A designates a building-block which is made in the form of a parallelopiped, but which may be made in the form of a cube, or in any 30 other form suitable for the purpose for which the block is to be used. The faces $a-a'$ of this block, which are opposite to each other, are provided with cavities $b-b'$, the cavities b in the face a being made to extend to within a 35 short distance from the opposite face, a' , and the cavities b' in the face a' to within a short distance from the opposite face, a . (Best seen in Figs. 2 and 3.) The remaining faces, ℓ , of the block A present solid or unbroken surfaces.

40 The cavities $b-b'$ are produced by pins $d-d'$, Fig. 4, which extend in opposite directions from heads $e-e'$, through the top f and bottom g of the mold C, which contains the clay or other plastic material from which the block is to be 45 made. From this drawing it will be seen that the pins $d-d'$ lie close together when they have been forced into the clay, so that hollow spaces h , Fig. 2, are formed, which extend to the outside walls of the block, and which are separated from each other by partitions i . The 50

pins $d-d'$ may, however, be so placed that they do not touch when forced into the clay, and that the cavities b , made by the pins d , remain distinct from the cavities b' , made by the pins d' . In the example shown in the drawings the cavities $b-b'$ are square; but these cavities may be round, or of any other desirable form or shape. 55

When the mold has been charged with the plastic material its top is put on and the pins $d-d'$ are forced in. By the action of the pins 60 a powerful pressure is exerted on the clay or other plastic material, and the finished blocks are rendered solid and durable.

My building-block is intended particularly for partition-walls in buildings, and it has the 65 great advantages that it is light, that it presents two perforated faces, which retain the plastering firmly, and that its remaining faces are solid or unbroken, so that they present proper surfaces for mortar. The cavities in 70 the faces intended to retain the plastering also afford an opportunity for nails to be driven into the partition-walls made of my blocks.

It will be understood from the foregoing description that the weight of my blocks can be 75 increased or decreased by changing the distance between and the size of the cavities $b-b'$.

What I claim as new, and desire to secure by Letters Patent, is—

1. A building-block two opposite faces of 80 which are provided with cavities, the cavities in each of said faces extending to within a short distance from the opposite face, while the remaining faces present solid or unbroken surfaces, substantially as shown and described. 85

2. The within-described process for producing building-blocks by placing clay or other suitable plastic material into a mold the top and bottom of which are provided with perforations, and then forcing from opposite sides, 90 through these perforations, suitable pins for pressing the clay and producing cavities in two opposite sides of the block, as set forth.

In testimony whereof I have hereunto set my hand and seal in the presence of two subscribing witnesses.

JOHN J. SCHILLINGER. [L. S.]
